UNITED STATES PATENT OFFICE.

JOHN O. HUNT, OF BROOKLYN, NEW YORK, ASSIGNOR TO INDEPENDENT PAPER MILLS, INC., OF BROOKLYN, NEW YORK.

TOWEL DISPENSER.

Application filed March 17, 1926. Serial No. 95,449.

This invention relates to cabinets and particularly to such as are adapted for use in connection with paper towels and other articles of analogous nature.

5 It is one object of the invention to provide a cabinet in which such commodities may be safely stored in a sanitary condition, free from handling, and from which they may be delivered singly by proper manipulation.

10 A further feature is in the provision of a follower resting on the uppermost article by which they are urged into an accessible position, and to combine with the follower a simple but effective device to prevent an unwarranted rising movement of the follower until depletion of the stock.

20 Another aim is in the production of means to automatically release and retract the follower coincidently with raising the front panel, as in replenishing the cabinet.

25 A still further object is to produce an inexpensive cabinet of attractive appearance, constructed mainly from sheet metal and adapted to be secured to any vertical wall where it is conveniently accessible.

30 These several objects are insured by the characteristic features of the present invention as herein described and shown in the associated drawing forming part hereof, and in which:—

Fig. 1 is a front elevational view of an embodiment of the invention, partially broken away to show the construction and relation of parts.

35 Fig. 2 is a longitudinal sectional view taken on line 2—2 of Fig. 1.

Fig. 3 is a transverse sectional view taken on line 3—3 of Fig. 1.

40 Fig. 4 is an enlarged fragmentary sectional view of the follower in detail.

The cabinet consists of a sheet metal plate sheared and shaped to present an oblong rectangular rear wall 10, top plate 11, side walls 12 and an angularly outstanding raised face plate 13, the latter element containing a transverse rectangular opening 14 having fancifully formed corners and outwardly curved, smoothly finished flanged edges 15, through which the towels X may be withdrawn singly.

45 The front edges of the side walls 12 are curled oppositely to produce beadings 16 extending from the top plate 11 to just above the junction of the face plate flange 17, these 50 beadings being open at their inner facing

sides to receive a slidable plate 18, provided with a knob 19 or like lifting means, the plate fitting the beading neatly at its sides and entering below the flange 17 when fully inserted to completely cover the front of the 60 structure.

The towels X are pressed lightly against the inner surface of the inclined face plate 13 by a follower composed of a sheet metal plate 20 having divergently widened end 65 portions 21 provided with raised angular side flanges 22 blending into main side flanges 23 over the edges of the main parallel portion of the plate, the bottom being flat and level throughout.

Set midway in the width and at uniformly spaced distances from the longitudinal center of the plate, are headed studs 24, their bodies passing freely through openings in a pair of curved plates 25 resting on the plate 70 20 at points 26 outwardly beyond the studs 24 as best seen in Fig. 4.

On one of the raised adjacent ends of the curved plates is secured a clip 27 bridging the variable space 28 therebetween and extending over the opposed edge of the mating plate to transmit motion to it when depressed so as to cause them to move in unison.

On the outer, reduced angular ends 29 85 of the plates are secured frictional elements 30, as blocks of rubber, which, due to their weight, tend to rock the plates upon their contact points 26 within the limit of the length of the studs 24 on which they freely move.

The plate 20 is so proportioned as to operate freely within the casing and the curved, friction block carrying plates are so contrived as to permit ready descent of the follower, but upon an attempt to raise the follower the friction blocks engage the inner surfaces of the side walls of the casing and positively prevent such movement.

It is therefore necessary to raise the blocks 30 preliminary to elevating the follower as an entity, which may be accomplished by depressing the clip 27 by hand or automatically by lifting the cover plate 18, to the lower edge of which are attached fingers 31 100 inreaching and bent to avoid confliction with the stock of towels X but contact with the plate 25 carrying the clip 27, thus swinging both blocks 30 out of engagement with the 105 walls of the casing.

Although the foregoing is descriptive of the preferred embodiment of the invention, it will be apparent that minor changes may be made in its construction, without the 5 claims hereto appended.

Having thus described my invention, what I claim as new and desire to secure by Letters Patent, is:—

1. In a towel dispenser, a receptacle provided at one end with an opening for the manual withdrawal of its contents, a follower adapted to move and hold the said contents in position in the said opening, the said follower comprising a metal plate having widened end portions, studs set in the plate, a pair of curved plates pivotally mounted on the plate and resting on the

plate at points outwardly beyond said studs, frictional elements mounted on the outer elements of said curved plates, said frictional elements being arranged to engage the side walls of the receptacle. 20

2. In a towel dispenser, a receptacle provided at one end with an opening for the manual withdrawal of its contents, and a follower adapted to move and hold the said contents in position in said opening, the said follower comprising a metal plate, and a pair of curved plates pivotally mounted on the plate, frictional elements mounted on the outer ends of such curved plates to engage the side walls of the receptacle. 25 30

JOHN O. HUNT.
